UNITED STATES PATENT OFFICE.

HENRY HYMAN, OF BROOKLYN, NEW YORK, ASSIGNOR TO HENRY HYMAN & CO., INC.,
OF NEW YORK, N. Y., A CORPORATION OF NEW YORK.

BATTERY HANDLAMP.

Application filed October 6, 1923. Serial No. 666,944.

To all whom it may concern:

Be it known that I, HENRY HYMAN, a citizen of the United States, and residing at Brooklyn, New York, county of Kings, have 5 invented the new and useful Improvement in Battery Handlamps, of which the following is a specification.

This invention relates to battery hand lamps, and more particularly to such lamps 10 having metal casings. The invention is also particularly adapted to that type of lamps having flared heads adapted to receive an enlarged lens and reflector.

One of the objects of this invention is to 15 provide improved means for insulating and supporting the reflector, and positioning the same and the lamp in the casing.

Another object of this invention is to provide improved means for receiving the thrust 20 of the battery so as to relieve the lamp thereof.

Another object of this invention is to provide an improved construction for supporting, centering, and insulating the reflector 25 which shall be simple and cheap to manufacture, and reliable in service.

Further objects will appear from the detail description taken in connection with the accompanying drawing, which represents a 30 central vertical section of a hand lamp embodying this invention.

Referring to the accompanying drawing, 1 designates the casing which, in the present case, is of metal and is provided with a 35 shoulder 2 adjacent the lamp end thereof and a threaded portion 3 adapted to receive a corresponding threaded portion of a flared head 4.

Mounted within the casing 1 and resting 40 on the shoulder 2 is an insulating ring 5. This ring may be constructed of fibre or other suitable insulating material, and may be either solid or split at one portion of its circumference so as to provide a snug fit in 45 the end of the casing. This ring extends from the shoulder 2 substantially to the upper end of the casing.

Mounted in the insulating ring 5 is a reflector support comprising an insulating disc 6 adapted to rest at its rim upon the upper 50 edge of the ring 5 and having a central opening in which is mounted an eyelet or socket 7. Fixed to the disc 6 at the eyelet 7 is a metallic cup 8 provided with a downwardly 55 extending flange or rim 9. The rim 9 is

adapted to fit snugly but not too tightly within the insulating ring 5 so as to properly center the reflector support in the casing.

Mounted on or integral with the socket 7 is an extension 10 provided near its lower 60 end with an internal bead 11. Mounted in the extension 10 and resting against the bead 11 is an insulating disc 12 retained in place by spinning over the edge 13 of the extension or in any other suitable manner. The insulating disc 12 is provided with a central opening within which is mounted a cup 14 adapted to contact with the central terminal 15 of the battery. Mounted within the cup 14 is another inverted cup 16 having an out-turned flange 17 adapted to engage an in-turned flange 18 on the cup 14 so as to prevent separation of the cups. Confined within the two cups is a spring 19 which tends to press the two cups apart. The cups 14 65 and 16 with their included spring 19 provide a yielding contact device connecting the central terminal of the lamp 20 with the battery terminal 15.

The reflector 21 is provided with the usual 80 nipple 22 to receive the lamp 20. The reflector 21 is mounted with its nipple 22 within the socket 7 so as to properly position the lamp 20 for engagement with the yielding contact device 14-16. This mounting also 85 centers the reflector so that when its rim is engaged by the lens 25 mounted on the head 4 in any usual manner, the reflector will be supported out of contact with the casing.

A contact strip 23 extends from the usual 90 thumb-switch (not shown) on the casing to the rim 9, lying between said rim and the insulating ring 5 so as to provide a circuit connection to that rim and to the reflector. The path of the current starting from the 95 lower battery terminal lies through the casing which is in contact with said terminal, through the thumb-switch when closed, through the strip 23 to the rim 9, thence through the cup 8 to the socket 7, thence 100 through the reflector to the lamp 20, through the lamp to the central terminal thereof and thence through the yielding contact device 16-14 to the upper terminal 15 of the battery.

When the reflector support has been assembled in the casing, it is retained in place by screwing down the rim 24 formed on the head 4 so as to hold the support securely in place.

It will be noted that in accordance with this invention, the reflector part of the circuit is entirely insulated from the casing and the head. The reflector support serves to center the reflector with respect to the head so as to maintain the same out of contact with said head. At the same time the socket 7 serves to properly position the lamp 20 for engagement with the yielding contact device. The thrust-receiving device including the extension 10, the insulating disc 12 and the lower cup 14 serves to transmit the thrust of the battery directly to the casing and to relieve the lamp and the reflector from all stresses incident thereto. The lamp is thus protected from shocks due to dropping the casing and similar accidents.

It is obvious that various changes may be made in details of construction without departing from the spirit of this invention; it is, therefore, to be understood that this invention is not to be limited to the specific details shown and described.

Having thus described the invention, what is claimed is:

- 25 1. In a battery hand lamp having a battery-receiving casing provided with a flared head and a reflector and a lamp therein, an insulated reflector support mounted in and independently secured to the casing and having a socket, adapted to support and center the reflector in the head.
- 25 2. In a battery hand lamp having a battery-receiving casing provided with a flared head and a reflector and a lamp therein, an insulated reflector support mounted in and independently secured to the casing and having a socket contacting with the reflector, adapted to support and center the reflector in the head, and a circuit connection to said support.
- 25 3. In a battery hand lamp having a battery-receiving casing provided with a flared head and a reflector and a lamp therein, an insulating ring in the casing, an insulating disc resting on said ring and having a metallic rim internally engaging said ring, a metallic socket on said disc and connected with said rim and adapted to receive and center the reflector in the head, and a circuit connection to said rim.
- 25 4. In a battery hand lamp having a battery-receiving casing provided with a flared head and a reflector and a lamp therein, an insulating ring in the casing, an insulating disc resting on said ring and having a metallic rim internally engaging said ring, a metallic socket on said disc and connected with said rim and adapted to receive and center the reflector in the head, and a circuit con-

ductor within said ring and contacting with said rim.

5. In a battery-hand lamp having a battery-receiving casing provided with a flared head having a rim and a reflector and a lamp therein, an insulated reflector support secured in the casing by engagement with said rim and having a socket, a device on said support adapted to take the thrust of the battery, and a contact on said device adapted to yieldingly connect the lamp with the battery.

6. In a battery hand lamp having a battery-receiving casing provided with a flared head and a reflector and a lamp therein, an insulating ring in the casing, an insulating disc resting on said ring and having a metallic rim internally engaging said ring, a metallic socket on said disc and connected with said rim and adapted to receive and center the reflector in the head, a device connected with said socket adapted to take the thrust of the battery, and a contact on said device adapted to yieldingly connect the lamp with the battery.

7. A battery hand lamp comprising, a battery-receiving casing, an insulating ring fitting the reflector end of said casing, a support having a socket and a rim fitting said ring, and a reflector seated in said support and engaging said socket.

8. A battery hand lamp comprising, a battery-receiving casing, an insulating ring fitting the reflector end of said casing, a support having a socket and a depending flange fitting said ring, and a reflector seated in said support and engaging said socket.

9. A battery hand lamp comprising, a battery-receiving casing, an insulating ring fitting the reflector end of said casing, a support having an insulating disc provided with a depending flange fitting said ring, and a reflector seated in said support.

10. A battery hand lamp comprising, a battery-receiving casing, an insulating ring fitting the reflector end of said casing, a support having a socket and a rim fitting said ring, a reflector seated in said support and engaging said socket, and a contact strip between said support and said ring.

11. A battery hand lamp comprising, a battery-receiving casing, an insulating ring fitting the reflector end of said casing, a support having a rim fitting said ring, a reflector seated in said support, and a thrust-receiving device on said support and engaging the battery.

In testimony whereof I affix my signature this 24th day of September, 1923.

HENRY HYMAN.
